US00D828041S

(12) United States Design Patent (10) Patent No.: US D828,041 S
 Adam et al. (45) Date of Patent:  Sep. 11, 2018

(54) FABRIC WITH CAMOUFLAGE PATTERN

(71) Applicants: Steven Bradley Adam, College Station, TX (US); Ryan D. Yates, Spring Branch, TX (US)

(72) Inventors: Steven Bradley Adam, College Station, TX (US); Ryan D. Yates, Spring Branch, TX (US)

(73) Assignee: XOTIC CAMO AND FISHING GEAR, LLC, College Station, TX (US)

() Term: 15 Years

(21) Appl. No.: 29/604,263

(22) Filed: May 16, 2017

(51) LOC (11) Cl. 05-03

(52) U.S. Cl.

USPC D5/28; D5/32

(58) Field of Classification Search

USPC D5/2, 3, 4, 7, 11, 19, 23, 25, 43, 47, 48, D5/51, 53, 55, 57, 59, 6, 16, 24, 32, 66; D6/612, 613, 617, 596, 601, 602, 603, D6/608, 611, 616; D19/1, 5; 15/208; 28/143, 160, 163; 112/401; 428/66.5; 442/408
